UNITED STATES PATENT OFFICE.

THOMAS AVERY CORRY, OF AREQUIPA, PERU.

PARABOLIC-MIRROR-GRINDING MACHINE.

1,171,174.

Specification of Letters Patent.

Patented Feb. 8, 1916.

Application filed October 16, 1914. Serial No. 866,952.

To all whom it may concern:

Be it known that I, THOMAS A. CORRY, a citizen of the United States, and a resident of Arequipa, Peru, have invented a new and Improved Parabolic-Mirror-Grinding Machine, of which the following is a full, clear, and exact description.

This invention relates to machines or apparatus for the manufacture and finishing of

10 optical lenses or special forms of reflecting mirrors, and has particular reference to machines for concaving and polishing parabolic reflecting mirrors such as are used particularly in reflecting telescopes, headlights, etc.

15 Among the objects of the invention is to provide a device of a practical and reliable nature and which, when once adjusted, is adapted to operate practically automatically for the purpose of grinding or concaving a 20 piece of work and which produces a concavity substantially parabolic within the practical range of the machine.

The foregoing and other objects of the invention will hereinafter be more fully described and claimed and illustrated in the drawings forming a part of this specification in which like characters of reference indicate corresponding parts in all the views, and in which—

25 50 Figure 1 is a front elevation of a preferred embodiment of the machine, parts being in section; Fig. 2 is a side view of the same, also partly in section; Fig. 3 is a view corresponding to the upper portion of Fig. 2 but indicating a modified form of counter balancing means for the grinding tool; Fig. 4 is a modification of the lower portion of Fig. 1 indicating one preferred form of mechanism for manipulating the grinding 35 40 instrument automatically, and Fig. 5 is a vertical section of the central part of Fig. 1 on a plane parallel to that of Fig. 1.

The several parts of the device may be made of any suitable materials, and the relative sizes and proportions, as well as the general design of the mechanism, may be varied to a considerable extent without departing from the spirit of the invention hereinafter more fully set forth and specifically claimed.

45 50 Referring more particularly to the drawings, I show a main frame comprising practically three legs or standards 10 having their feet connected at 11 to a base 12 adapted to be supported in any suitable manner in a substantially horizontal position. The

upper ends of the legs are secured to an annulus or collar 13 having an open center and arranged in a substantially horizontal plane. The two side legs are arranged substantially 60 diametrically opposite from each other and the other leg is arranged in the rear thereof, leaving the front of the machine free for the mounting and operation of the active portions thereof.

65 At 14 I show a vertical rotary tool shaft supported substantially centrally with respect to the annulus 13 within which the shaft is adapted to oscillate in a plane parallel to the vertical plane of the two side 70 legs 10 and around an axis extending through the annulus 13 from front to rear. The shaft 14 is journaled at its upper end in a clamp 15 and a sleeve 16 projecting upwardly therefrom. The clamp is provided 75 at the front and rear with a pair of arms 17 having cone bearing connections with a pair of adjustment screws 18 extending horizontally through the annulus.

80 A suspension rod 19 is connected at its upper end to the clamp 15 and at its lower end is fitted loosely in a bearing block 20. A block 21 is secured to the rod 19 above its lower end. The shaft 14 is journaled in the blocks 20 and 21 but is free to slide vertically within said blocks.

85 90 22 indicates a suitable grinding or polishing tool adjustably fitted to the lower end of the rotary shaft.

From the nature of the clamp 15 and the blocks 20 and 21, the shaft 14 and suspension rod 19 are maintained parallel to each other, and by reason of described connections between the shaft and the blocks 20 and 21 of the suspension rod, the shaft is 95 supported from or by the rod for operation upon the work, as explained more in detail below.

100 105 At 23 I show a sleeve arranged between the blocks 20 and 21 and in which the shaft is journaled antifrictionally by means of collars 24 and 25 secured to the shaft and between which collars and the sleeve bearing balls are located. An arm 26 is secured to the sleeve 23 and projects laterally therefrom, the arm having a surface 26' along its lower edge which is substantially perpendicular to the axis of the shaft. A slide 27 bears upwardly against the surface 26' of the arm and said slide is journaled upon a horizontal axis 28 extending between pairs of pantographic arms or toggle links 29 and

110

30, the pivot or axis passing through selective holes formed in the links 29, whereby the relative lengths of the links 29 and 30 may be varied. The upper ends of the links 5 29 are pivoted at 31 to the clamp 21 and the lower ends of the lower links 30 are pivoted at 32 to the end of an arm 33 secured rigidly to and carried by a slide 34 movable preferably in a straight horizontal line along a 10 bar 35 supported upon the side legs 10 and constituting what may be termed a directrix. It will be understood that the toggle links 29 and 30, together with the slide 27, constitute the main support for the arm 26 and 15 rotary shaft 14 and hence these elements constitute a stop limiting the downward movement of the shaft and the tool secured thereto.

The action of gravity upon the shaft 14 20 and parts carried thereby is counteracted to a greater or less extent by any suitable counterpoise devices. As shown in Fig. 1, there is employed a coil spring 36 acting upwardly upon the shaft and supported upon the clamp 21. The effect of the spring is 25 variable by virtue of a winged nut 37 at the upper end of the spring. In Fig. 3, however, is shown another counterpoise device which comprises a weight pan 38 having a 30 flexible connection 39 leading therefrom over direction pulleys 40 to a swivel 41 connected to the upper end of the shaft 14. The adjustment of the effect of gravity upon the shaft and tool is necessary particularly 35 in the finishing of a lens or mirror.

The slide 34 is adapted to be operated along the directrix by any suitable means, either by hand applied to a handle 42 or by means of mechanical devices such as shown 40 in Fig. 4. In this figure is shown a cross head 43 slidable along guideways 44 extending horizontally and outwardly from one of the legs 10. The cross head has a link 45 connecting it to the pivot 42' of the slide 45 and the cross head is operated by means of a pitman 46, the outer end of which is adjustably connected at 47 radially along a disk 48 mounted upon a shaft 49 and shown as adapted to be driven by means of wheels 50 and 51 connected by a belt 52. The radial adjustment of the pitman 46 is necessary or advisable according to the diameter of the mirror or lens operated upon or in accordance with the amplitude of movement 55 of the tool 22. The axis 31 pertaining to the upper pivots for the links 29 carried by the clamp 21 bears a constant relation to the axis 17 around which the operating parts oscillate, and hence, as shown in Fig. 1, the 60 point 31 must swing in the arc of a true circle. The point 32 bearing a constant fixed relation to the slide 34 must move in a straight horizontal line or a line parallel to the directrix. It follows, therefore, that 65 when the slide is moved in either direction

from the normal or mid position shown in full lines in Fig. 1, the two points 31 and 32 move apart. Since the links 29 and 30 are pivoted together on the point or axis 28 and have their opposite ends pivoted to the 70 points 31 and 32, it follows that the point 28 is caused by the oscillation of the shaft to describe a curve of a character intermediate the straight line described by the point 32 and an arc of a circle described by the point 75 31. The slide 27 carried by the axis 28 will therefore define or determine the path of movement of the tool 22 by reason of its co-operation with the arm 26 and sleeve 23 supporting the shaft 14. 80

With the parts arranged and proportioned substantially as indicated in Fig. 1, the path of movement of the active point of the abrading tool 22 is substantially a true parabola within the practical arc of oscillation, the focal center of the parabolic curve coinciding with the axis of oscillation of the shaft 14. It is obvious, however, that the form of the curve may be varied by variously adjusting the relation between the several points indicated. For instance, by lowering the point 28, a flatter concavity will be produced, and by increasing the distance between the point of the tool and the point 32, the concavity is deepened or the curve 95 formed by the tool is sharpened.

The plate or job being treated and shown at 53 is supported in operation upon a turntable 54 secured to a spindle 55 preferably of conical form and journaled in a bearing 100 socket 56. Said socket and parts carried therein are adjustable vertically by means of a set screw 57 operating through the bottom of a casing or holder 58 shown as secured to the central portion of the bed plate 105 12. The turntable may be caused to rotate at any desired speed and by any suitable means. I prefer, however, to rotate it comparatively slowly by means of a worm 59 co-operating with teeth 60 formed upon the 110 periphery of the turntable and thereby constituting the turntable as a worm gear. The worm 59 is shown as mounted upon a shaft 61 which is driven by miter gears 62 from a vertical power shaft 63 journaled in the 115 main frame of the machine. A main driving wheel 64 is secured to the shaft 63 and may be operated by means of a belt 65. To the upper end of the shaft 63 is secured a belt wheel 66 having a belt 67 leading therefrom to a small pulley 68 journaled upon the aforesaid bearing sleeve 16. Pins 69 and 70 carried by the pulley and shaft 14 respectively serve to insure the rotation of the shaft from the pulley while allowing a comparatively free slidable movement of the shaft. The pin 70 is connected to a collar 71 rigidly secured to the upper end of the shaft. By virtue of the sleeve 16 the strain of the belt 67 upon the pulley is relieved 120 125 130

from the shaft and hence all unnecessary friction between the shaft and its bearings is prevented.

Having thus described my invention, I 5 claim as new and desire to secure by Letters Patent:—

1. In a machine of the character set forth, the combination of a support, a suspension member mounted upon a horizontal pivot 10 in said support and adapted to oscillate around its pivot, a rotary shaft arranged in said suspension member and adapted to oscillate therewith, means to rotate the shaft, a tool carried by the free end of the 15 shaft, and means coöperating with the suspension member and the rotary shaft serving to cause the active point of the tool to describe a parabolic curve while the suspension member oscillates in the arc of a 20 circle.
2. In a device of the character set forth, the combination of a rotary shaft, means to support the shaft for oscillation around a fixed axis but allowing the shaft to slide 25 transversely of said axis, means to rotate the shaft in its support, a tool carried by the free end of the shaft, and means coöperating with the shaft and its supporting means serving to cause the point of the tool to 30 describe a parabolic curve whose focal center coincides with the axis of oscillation of the shaft.
3. In a machine of the character set forth, the combination of a main supporting frame 35 including a horizontal annulus adjacent its top, a rotary shaft extending centrally of said annulus, means pivotally supporting the shaft on a fixed axis in said annulus and permitting the oscillation of the shaft 40 around said axis, said shaft supporting means including a rigid member adapted to swing with the shaft in an arc of a circle, a tool secured to the free end of the shaft, a rigid stationary member adjacent the 45 plane of oscillation of the shaft, a slide movable to and fro on said stationary member along a path different from an arc of a circle, and means connected to said slide and coöperating with the shaft and its supporting 50 means serving to cause the tool to describe a path having a form differing from both the path of the slide and an arc of a circle.
4. In a machine of the character set forth, 55 the combination of a supporting frame in-

cluding a horizontal annulus, a rotary shaft journaled within the frame and having its axis extending through the annulus, a rigid supporting member for the shaft including bearing arms journaled in a horizontal axis 60 in the annulus and including bearings in which the shaft rotates, every point of the rigid supporting member being adapted to oscillate in an arc of a circle around the pivotal axis of the shaft, a tool carried by 65 the free end of the shaft and movable with the shaft longitudinally in its bearings, a rigid stationary member arranged transverse to the normal mid-position of the shaft, a slide fitted to the stationary member 70 and movable to and fro thereon and describing a path differing from an arc of a circle, a pair of members pivoted together and having their opposite ends pivoted respectively to the rigid shaft supporting the said slide, 75 and means coöperating with said pair of members and the shaft serving to cause the tool to describe a path differing both from that of the slide and an arc of a circle, substantially as set forth.

5. In a machine of the class set forth, the combination of a main support, a rotary shaft, means to support the shaft in the main support for oscillation around a horizontal axis, said shaft support including 80 bearing members in which the shaft is journaled and adapted to slide longitudinally, a tool carried by the free end of the shaft, a rigid stationary member adjacent the path of movement of the shaft, a slide movable to 85 and fro along the stationary member in a straight line, a pair of links pivoted together and having their opposite ends pivoted respectively to the rotary shaft support and said slide, an arm associated with the rotary 90 shaft, means to prevent relative longitudinal movement between the arm and shaft, and a member associated with the point of connection between the links and coöperating with said arm whereby the tool will be 95 caused to describe a parabolic curve simultaneously with the operation of the shaft and support.

In testimony whereof I have signed my name to this specification in the presence of 105 two subscribing witnesses.

THOMAS AVERY CORRY.
